UNITED STATES PATENT OFFICE.

BENJAMIN F. ENNIS AND JAMES CARR, OF SYRACUSE, NEW YORK.

DESIGN FOR A CIGAR-CLIPPING CASE.

SPECIFICATION forming part of Design No. 23,140, dated March 20, 1894.

Application filed January 22, 1894. Serial No. 497,713. Term of patent 3½ years.

To all whom it may concern:

Be it known that we, BENJAMIN FRANK ENNIS and JAMES CARR, citizens of the United States, residing at Syracuse, county of Onondaga, and State of New York, have invented and produced a new and original Design for Cigar-Clipping Cases, of which the following is a specification, reference being had to the accompanying drawings, showing parts thereof. Figure 1, is a side view of the case showing our design. Fig. 2, is a top plan view thereof, these two views being deemed necessary to fully illustrate our design.

The leading feature of our design consists in an oblong case, the top of which sets over the body of the case; as shown in Fig. 1, the

whole forming a cigar-clipping case, as a unitary article.

—A— is the body of substantially the form shown; and —B— is the top resting upon the body, its outer edges projecting over the body forming a beading —a—.

What I claim is—

The design for a cigar clipping case substantially as herein described and shown. 15

In witness whereof we have hereunto set our hands this 19th day of January, 1894.

BENJAMIN F. ENNIS.
JAMES CARR.

In presence of—

M. M. BORST.
HOWARD P. DENISON.
